CLAIM

The ornamental design for a “motorcycle mirror”, as shown.

DESCRIPTION

FIG. 1 is a perspective view of a motorcycle mirror showing my new design the motorcycle mirror being shown attached to a conventional stem, the stem being shown in phantom lines;

FIG. 2 is a left side elevational view thereof, the motorcycle mirror being shown attached to a conventional stem, the stem being shown in phantom lines, the right side elevational view is a mirror image of the left side;

FIG. 3 is a front view thereof;

FIG. 4 is a rear view thereof;

FIG. 5 is a top view thereof, the motorcycle mirror being shown attached to a conventional stem, the stem being shown in phantom lines; and,

FIG. 6 is a bottom view thereof, the motorcycle mirror being shown attached to a conventional stem, the stem being shown in phantom lines.

The phantom lines are for purposes of illustration only and form no part of the claimed design.
